UNITED STATES PATENT OFFICE.

EDWARD B. POGGENSEE, OF CHICAGO, ILLINOIS, ASSIGNOR TO SANITARY BOTTLE WASHING COMPANY, LIMITED, OF CHICAGO, ILLINOIS, A CORPORATION OF ILLINOIS.

KITCHEN UTENSIL.

1,159,080.

Specification of Letters Patent.

Patented Nov. 2, 1915.

Application filed December 31, 1914. Serial No. 879,832.

To all whom it may concern:

Be it known that I, EDWARD B. POGGENSEE, citizen of the United States, residing at Chicago, in the county of Cook and State of Illinois, have invented a certain new and useful Improvement in Kitchen Utensils, of which the following is a full, clear, concise, and exact description, reference being had to the accompanying drawings, forming a part of this specification.

My invention relates to a utensil for aerating fluid food elements and which are commonly known as egg beaters or cream whippers.

The invention has for its general object the provision of an improved mounting for the beating element of the utensil whereby the range of operation thereof is substantially fixed to enable the continued operation of the beater at a given locality and whereby small quantities of the fluid to be beaten may be kept in constant agitation.

My invention also has for its object the provision of an improved form of beater, the use of which is enabled by the improved mounting thereof and which improved form of beater includes a plurality of flexible strands which are desirably in the form of coiled metallic springs that are bunched together at the upper ends thereof and are free of mounting at their lower ends to permit them to spread apart in opposition to their own resilience in responsive to centrifugal force, the strands being spread apart and brought together as the beater is turned in reverse directions. The aeration of the fluid undergoing the beating operation is also improved by the preferably employed hollow formation of the beating strands and by the interstices which intervene between the helices of the strands when formed in the shape of coiled metal springs.

I will explain my invention more fully by reference to the accompanying drawing showing the preferred embodiment thereof and in which—

Figure 1 is a view in sectional elevation of a structure made in accordance with the invention; Fig. 2 is a plan view, on a reduced scale, on line 2 2 of Fig. 1; Fig. 3 is a view on line 3 3 of Fig. 1; and Fig. 4 is a detail view, on a larger scale, of one of the strands of the beater.

Like parts are indicated by similar characters of reference throughout the different figures.

The vessel 1 (preferably substantially cylindrical upon its exterior) in which the fluid to be beaten is disposed desirably has an outwardly flaring margin 2 over which the inwardly tapering rim 3 of a top or cover 4 may be sprung. The top 4 is provided with a central round opening 5 which is in axial alignment with the vessel. A lower horizontal upwardly facing stationary raceway wall 6 surrounds and is co-axial with the opening 5. The balls 7 of a ball bearing structure are disposed in the annular groove in the lower raceway wall 6 and are received within the annular groove in an upper horizontal raceway wall 8. This latter raceway wall is in fixed relation with the shaft 9 of the beating element of the utensil, this shaft being desirably formed of a spirally twisted bar of metal, rectangular in cross section, so as to constitute it a threaded shaft which is so commonly found in devices of this class. This threaded shaft passes through a ferrule 10 having an opening therein which closely approximates the cross section of the shaft, as illustrated in Fig. 3. The upper end of the shaft projects within a handle 11 and carries a spring seat 12 at its upper end in which is received the lower end of a coiled spring 13 whose upper end has abutting engagement with the top wall of the handle bore as illustrated clearly in Fig. 1.

When the handle is depressed rotation of the shaft 9 is forced owing to its threaded engagement with the nonrotating ferrule 10, and when downward pressure upon the handle is relieved the spring 13 (which was compressed on such downward movement of the handle) will serve to return the handle and thereby occasion a rotation of the shaft 9 in a direction which is reverse to that which was first imparted to such shaft. The shaft 9 is thus caused to rotate in a substantially fixed plane which is defined by the engagement of its enlargement 8 with the upper part of the top 4 and while this engagement is desirably effected through the intermediation of a roller bearing structure I do not wish to be limited to the employment of such a structure. The lower end

of the shaft is coupled with a sleeve 14, as by means of a cotter pin 15. This sleeve 14 constitutes a mounting for a plurality of flexible strands 16 which are desirably metallic and resilient, these strands being preferably free at their lower ends to respond to centrifugal force in opposition to their own resilience. When the handle 11 is depressed rotary movement is imparted to the shaft 9 in one direction which will cause the strands 16 to fly apart and when the handle is released to permit the spring 13 to function, the resilience of the strands will be first effected to cause their lower ends again to approach whereafter the strands will again fly apart when the spring 13 effects the elevation of the handle.

The inner surface of the bottom of the vessel desirably conforms to a segment of a sphere whose center approximates the lower end of the sleeve 14 so that none of the liquid within the vessel will be free of violent agitating influence of the beater. In the preferred embodiment of the invention the resilient strands 16 are desirably formed of spirally wound resilient phosphor bronze wire. The strands are thus made of cylindrical formation with longitudinal bores and with opportunity for the passage of air between the helices thereof into such bores whereby the aerating or beating function of the beater is materially improved. The top 4 constitutes the preferred form of mounting for preventing bodily movement of the shaft 9 longitudinally of itself but I do not wish to be limited to the location of the mounting nor to the confinement of the shaft to a fixed axis as I consider it to be broadly new with me to prevent the longitudinal movement of the shaft with respect to itself irrespective of the position it may occupy when such shaft is employed in

the operation of the novel beater of my invention.

While I have herein shown and particularly described the preferred embodiment of my invention I do not wish to be limited to the precise details of construction shown as changes may readily be made without departing from the spirit of my invention, but

Having thus described my invention I claim as new and desire to secure by Letters Patent the following:

1. A fluid beating utensil which includes a fluid holding vessel; a beater projecting within the vessel and formed of metallic coiled springs free of mounting at their lower ends to permit the springs to spread in response to centrifugal force; and a bearing for rotatably supporting the beater to permit it freedom of movement at its lower end.

2. A fluid beating utensil which includes a fluid holding vessel; a beater projecting within the vessel and formed of metallic coiled springs free of mounting at their lower ends to permit the springs to spread in response to centrifugal force; an upwardly extending threaded shaft upon whose lower end the beater is carried; a handle in threaded engagement with the shaft to force the rotation thereof in reverse directions as the handle is reciprocated; and a mounting for the shaft for substantially preventing bodily longitudinal movement of the shaft while permitting the rotation thereof.

In witness whereof, I hereunto subscribe my name this twenty-third day of December A. D., 1914.

EDWARD B. POGGENSEE.
